CLAIM

We claim the ornamental design for an under water intelligent tracking robot, as shown and described.

DESCRIPTION

FIG. 1 is a front view of the under water intelligent tracking robot, showing our new design;

FIG. 2 is a left side view for thereof;

FIG. 3 is a right side view thereof;

FIG. 4 is a rear view thereof;

FIG. 5 is a top view thereof;

FIG. 6 is a bottom view thereof; and,

FIG. 7 is a perspective view thereof.

The dashed broken lines in the drawings represent portions of the under water intelligent tracking robot that form no part of the claimed design.
